UNITED STATES PATENT OFFICE

167,019

STOCKING EXAMINATION AND REPAIR FORM

Edward W. Boedeker, Fort Wayne, Ind., assignor
to Gotham Hosiery Company, Inc., New York,
N. Y., a corporation of Delaware

Application September 18, 1950, Serial No. 12,243

Term of patent 14 years

(Cl. D47—5)

To all whom it may concern:

Be it known that I, Edward W. Boedeker, a citizen of the United States of America, residing at 1815 Alabama Ave., city of Fort Wayne, State of Indiana, have invented a new, original, and ornamental Design for a Stocking Examination and Repair Form, of which the following is a specification, reference being had to the accompanying drawings, forming part thereof.

Figure 1 is a plan view of a stocking examination and repair form, showing my new design;

Figure 2 is a side view, and

Figure 3 is an enlarged end view thereof;

Figure 4 is an enlarged cross-sectional view taken on line 4—4; while

Figure 5 is an enlarged view of the end opposite to that shown in Figure 3.

I claim:

The ornamental design for a stocking examination and repair form, as shown.

EDWARD W. BOEDEKER.
